CLAIM

The ornamental design for portable phone holder and solar charger, as shown and described.

DESCRIPTION

FIG. 1 is a front top right perspective view of the portable phone holder and solar charger of the invention in its closed configuration.

FIG. 2 is a top view thereof.

FIG. 3 is a bottom view thereof.

FIG. 4 is front top right perspective view of the portable phone holder and solar charger of the invention in a first flipped open configuration.

FIG. 5 is a front top right perspective view of the portable phone holder and solar charger of the invention in a second flipped open configuration; and,

FIG. 6 is front top right perspective view of the portable phone holder and solar charger of the invention in the second flipped open configuration shown carrying a phone in phantom.

The broken lines shown in the drawings are included for the purpose of illustrating environmental structure and form no part of the claimed invention.
